UNITED STATES PATENT OFFICE.

MARSHALL BURNS LLOYD, OF MENOMINEE, MICHIGAN, ASSIGNOR, BY MESNE ASSIGNMENTS, TO THE ELYRIA IRON & STEEL COMPANY, OF ELYRIA, OHIO, A CORPORATION OF OHIO.

PROCESS OF MANUFACTURING METAL TUBING.

1,120,209.

Specification of Letters Patent.

Patented Dec. 8, 1914.

Application filed April 6, 1912, Serial No. 689,093. Renewed May 13, 1914. Serial No. 838,389.

To all whom it may concern:

Be it known that I, MARSHALL B. LLOYD, a citizen of the United States, and a resident of Menominee, county of Menominee, 5 and State of Michigan, have invented a certain new, useful, and Improved Process of Manufacturing Metal Tubing, of which the following is a full, true, clear, and exact description, such as will enable other skilled 10 in the art to make and use the same.

My invention relates to the art of making metallic tubing and has particular reference to improvements in the manufacture of tubing from strip metal.

15 The object of my invention is to rapidly and economically manufacture tubing of any cross-sectional shape from strip metal, and a further object of my invention is to produce from strip metal stock butt welded 20 metal tubing which shall be of any desired cross-sectional shape.

Other objects of my invention will appear hereinafter.

My invention resides in a process of manufacturing tubing from raw stock, such as 25 cold or hot rolled strip steel, and comprises a succession of steps whereby flat strip stock is converted into a complete butt-welded tube of desired cross section.

30 My novel process further consists in initially or preliminarily forming the flat strip of metal into a tube of non-circular cross-section, for instance, oval with its edges in seam relation, and while the tube is in this 35 condition and aided by its non-circularity, welding the edges to close the seam, and then forming the welded tube into the desired cross sectional shape; it being understood, however, that the tube after being 40 welded may be left in its initially formed condition if desired.

More specifically defined my improved process consists in first forming or bending the strip of metal to give it a preliminary 45 non-circular shape with its edges in abutting relation, moving it forward in this condition at a constant speed and utilizing its non-circularity to present its seam in a definite predetermined line, progressively welding 50 the seam, with or without the aid of pressure or auxiliary metals, as fast as the tube travels; and then, if desired, subjecting the welded tube to the action of mechanisms which cause it to assume its final shape.

55 The accompanying drawings forming a

part of this specification illustrate mechanisms and apparatus which I find well suited to the carrying out of my novel process.

In these drawings: Figure 1 illustrates 60 one form of apparatus adapted to the purposes of my invention; Figs. 2, 3, 4, 5 and 6 are sectional views showing the evolution or development of one form of tube in accordance with my invention; Figs. 7 and 8 are detail sectional views showing the initial 65 forming of a strip of metal into an oval tube; Fig. 9 is an enlarged sectional view of the dies or rolls for giving the tube a final circular form after its seam is welded; Figs. 10 and 11 are enlarged sectional views 70 of the mechanism for moving the tube forward and positioning its seam as the welding thereof takes place; Fig. 12 is a top plan view of the tube propelling and positioning mechanism; and Fig. 13 is a transverse vertical sectional view of said mechanism showing 75 the welder.

The strip of metal 7 (Fig. 2) usually 80 comes from the mills cut or rolled flat to the width and thickness for the desired size and shape of tubing, and either in tube 85 lengths or in longer lengths to be cut into tube lengths. If circular tubing T, such as shown in section in Fig. 6, is the ultimate form desired, the strip stock 7 is passed through the first step of my process, that is 90 the initial or preliminary forming step and caused to assume a non-circular sectional shape, for instance, oval, as in Fig. 4. After being formed in this manner this initially or pre-formed tube is subjected to a 95 welding operation which closes the seam and places the tube in condition for the final forming operation. It must be understood, however, that while this latter operation is quite essential to the production of extremely accurate and perfect tubing, especially circular tubing, it may be dispensed with in cases where the tubing is to be used 100 in the non-circular form as initially formed and welded, although I find that even in such cases a finishing operation produces more satisfactory results.

One of the important advantages in forming the metal into what might be called a 105 "preliminary tube" is that the tube can be better manipulated and the seam accurately welded, and after having been welded it possesses all the characteristics of so-called "seamless" or "drawn" tubing and is 110

thus admirably adapted to one or more drawing or compressing operations to give it its ultimate shape and finish.

In the drawings I have shown a simple but effective apparatus A for forming the strip of metal into a tube. This apparatus consists of two sets of rolls 1 and 2. My process contemplates the use of more or less rolls or dies for this purpose. The strip 7 is fed to the first set of rolls 1 wherein it receives a partial tube or half oval form, as clearly shown in Figs. 3 and 7, and from these rolls the metal passes preferably directly into a second set 2 which completes the oval tube shown in Figs. 4 and 8. It will be noted (Fig. 4) that the edges *t* of the strip are thus brought into abutting relation, upon a more or less straight line. The forming rolls or dies are mounted in alinement in a suitable frame A' supported on legs or standards A'' and may be driven by any suitable mechanism (not shown). The upper roll of each set is adjustable to and from its respective lower roll by means of the screws 5 and 6 for the purpose of regulating the forming pressure upon the metal. The strip of metal having been given the form of a non-circular tube, in this case oval, presents the cross sectional appearance shown in Fig. 4 and is ready to have its seam closed. This function is accomplished by the application of heat, with or without the aid of pressure or auxiliary metals or both as circumstances may determine. I find that excellent results are obtained by heating the tube to such temperature that the edges *t* of the tube are caused to flow together, and accompanying the heat with just sufficient pressure to properly effect a strong, uniform weld. The mechanism B which I have designed is admirably adapted to the performance of these functions. Herein the progressive or continuous weld is accomplished by a relative movement between the tube and a suitable heating device. In this mechanism or apparatus this continuous welding relation is obtained by propelling or moving the tube longitudinally forward, preferably at a constant speed, relatively to a stationary burner which plays a welding flame upon the seam of the tube as the tube travels. At the same time it maintains the tube edges in welding relation, exerts a welding pressure at the seam and automatically cooperates with and makes use of the peculiar shape of the tube to correct the irregularities therein and properly present the seam to the welding flame.

The apparatus B comprises a constantly traveling, tube-propelling and positioning mechanism above which is arranged an adjustable torch H which is adapted to play a localized welding flame upon the tube seam as it moves along thereunder, these parts being mounted in operative relation upon

a suitable frame B' supported on legs B'' to elevate them to a convenient position for an operator. The tube propelling mechanism illustrates one excellent structure by which certain steps of my novel process may be carried out. It may properly be called a continuous vise since it acts in the nature of a vise, being in fact composed of many little vises arranged in a traveling series to successively clamp the tube. In clamping the tube the vise automatically performs the important function of exerting a torsional or twisting force upon the non-circular tube to correct the irregularities therein and present the seam in alinement with the welding flame. The active portion of the tube carrier runs along the upper side of a bed plate D (Fig. 13). The vise sections are mounted upon and carried by a pair of endless chains C arranged in parallel, and running over the forward and rear sprockets 8 and 9 (Figs. 1, 11 and 12). The upper or active portion of the rotary vise travels in the direction of the arrow (Fig. 12) along the top of the bed plate D and the lower portion below the bed plate in the cooling trough 6 carried in the frame. The sprockets are mounted upon forward and rear shafts 10 and 11, respectively, the rear shaft 11 being driven by means of a suitable train of gears 12 from the main shaft 13 which is journaled in suitable bearings beneath the bed plate D. The shaft 13 in turn is driven through speed reducing worm gearing 14 from a belt driven shaft 15. Suitable clutch mechanism 16, for starting and stopping the carrier, is interposed in the train of gears 12 between the shaft 11 and the main shaft. Each of the chains C carries a series of the vise sections or clamping members 18 heretofore mentioned, the opposed sections being arranged in pairs, thereby forming a continuous vise composed of many short sections. As the whole mechanism travels the sections or pairs of jaws rise up around the forward end thereof into alinement with the tube which they successively clamp and convey to the flame of the burner. The jaws (Figs. 10 and 11) have removable gripping faces 18' which are conformed to the shape of the tube and which are preferably arranged to present to the flame the uppermost portion of the metal contiguous to the seam. The shape of the tube and the location of the seam are determining factors in the particular arrangement of the vise. In the oval tube shown, the seam is substantially in the plane of the longer axis of the oval and the vise is arranged to position the longer axis vertically. These conditions are altered somewhat when the tube seam lies in a different line than along the major axis. The sections move laterally and close upon the tube and in so doing they twist or rotate the tube and

force it into a straight line thus straightening the seam and alining it with the burner. The jaws or clamps of each pair are slidably mounted upon twin rods 20 (Figs. 10 and 11) which extend between the chains. Between each set of jaws is a spring pressed pin 21 which normally maintains the jaws spaced apart a distance slightly wider than the width of the tube so that as they rise up around the front end of the traveling vise they will freely clear the tube. The vise sections enter a long channel along the top of the bed plate D. This channel is formed by two long parallel guides G and G' (Fig. 12) having their forward ends 22 flared so that as the jaws enter the forward end of the channel these flared ends act as cams to force the jaws gradually toward each other and into clamping engagement with the tube. The clamping pressure exerted by the vise is maintained during the welding operation to hold the edges *t* of the metal in abutted relation while the flame plays upon them. This pressure also preferably exists for a sufficient time afterward to allow the joint to cool, this being one of the reasons for making the vise comparatively long. The rear end of the conveyer is provided with means for positively opening the jaws so as to relieve the pressure and release the tube. This opening mechanism comprises a wedge-shaped cam 23, shown in dotted lines in Fig. 12, which is positioned between the jaws. It acts to positively spread the jaws successively as they pass downward around the rear end of the conveyer. The guide or side wall G of the channel is adjustable to vary the width between the jaws by means of the set screws 24 and is clamped in its adjusted position by the bolts 25. The other guide G', however, is not fixedly clamped upon the bed plate D, but instead is provided with pressure regulating springs 26 interposed between the ends of the set screws 27 and the outer face of the guide, the springs being set in sockets 26' in the guide to prevent their displacement. Each vise section has small rollers 27' which reduce the friction incident to the movement of the jaws through the channel.

Obviously any suitable form of heating means may be used instead of the gas flame. I have, however, obtained excellent results with a gas flame composed of oxygen and acetylene in proper proportions. Thus the temperature, position and direction of the welding flame can be controlled by an oxy-acetylene torch or burner H adjustably positioned above the vise. This torch has a nozzle H' pointed diagonally downward toward the front of the machine and adapted to impinge or play a flame directly upon the seam of the tube as it travels. This flame heats to a welding or flowing tempera-

ture only the metal contiguous to the seam of the tube, and there is no tendency for the tube to crush or become weakened. The tube having been given its initial or preliminary non-circular form and its seam 70 having been thus uniformly welded, is ready to be subjected to one or more operations and thereby finally formed, except of course in cases where it is to be used in its initial form, in which event no further forming or 75 shaping operation will be necessary. For instance, the oval tube herein described may be used in its oval form. I prefer to carry the tube through one final shaping step to make it circular. The tube in its welded 80 condition has substantially all of the characteristics of the so-called "seamless" tubing and may be subjected to one or more drawing, rolling, stamping or compressing operations to reduce it in diameter or change its 85 cross-sectional shape. The apparatus P illustrates one way in which these functions may be performed. This comprises a set of compression dies 30 and 31 operating to compress the tube into circular form, as 90 shown in Fig. 9. The dies are arranged in a suitable frame, the lower die 30 being stationary and the upper one being reciprocated by the member 32. This is driven by a belt pulley from any suitable source of 95 power. These dies preferably compress a portion of the length of the tube at a time, as clearly shown in Fig. 1, hence it is desirable to have an automatic feeding device to feed the tube thereto. In the drawings 100 I have shown a feeding device comprising a lever 34 pivoted at 35 to the frame of the machine. One arm of this lever has a slot and pin connection 36 with the reciprocating member, and the other arm extends downward and operates the feeding clutch 37 so that when the machine is in operation the tube is fed intermittently to the dies by which it is compressed into circular shape.

It is to be understood that my novel 110 process is well adapted to the manufacture and production of tubes of other shapes and sizes, such as used in the various industries. The apparatus for carrying my process into effect in the manufacture of different sizes 115 and shapes of tubes may of course be varied as necessary to meet the different conditions.

The terms "weld," "welded" and "welding" as used herein are to be construed in their broad sense as meaning the uniting of 120 the edges by heat with or without the aid of pressure and with or without the use of auxiliary metals such as brass, iron and steel.

The welding mechanism herein disclosed 125 constitutes the subject matter of my companion application of even date herewith Serial Number 689,094.

I claim:

1. The herein described process of manu-

facturing metal tubes which consists in initially forming strip metal into a tube of non-circular cross section, moving the tube forward and exerting torsional strain thereon by reason of its non-circularity to force its seam into a predetermined position, and welding the seam of the tube as it travels with its seam in said predetermined position.

16 2. The herein described process of manufacturing metal tubes which consists in initially forming strip metal into a tube of non-circular cross section, moving the tube forward at constant speed and simultaneously exerting torsional strain thereon by reason of its non-circularity to forcibly position its seam as it travels, and welding the seam of the tube while in position.

3. The herein described process of manufacturing metal tubes which consists in initially forming strip metal into a tube of non-circular cross section, moving the formed non-circular tube forward and exerting torsional strains on the tube by reason of its non-circularity to straighten its seam, and welding the seam of the tube as it is straightened and, while the tube is in movement, causing a welding pressure at the seam.

30 4. The herein described process of manufacturing metal tubes which consists in initially forming strip metal into a tube of non-circular cross section, propelling the formed non-circular tube forward and torsionally forcing its seam into welding position, welding the seam of the tube as the tube travels and then finally forming said tube to the desired cross section.

5. The herein described process which 40 consists in initially forming a strip of metal into a tube of non-circular cross section, propelling the tube forward at constant speed and exerting torsional strains on the tube by reason of its non-circularity to force 45 its seam into a predetermined position, heating the tube to welding temperature and simultaneously causing pressure at the seam to progressively weld the latter as the tube travels, and, after the tube is welded, 50 subjecting it to an additional forming operation to give it a final cross-sectional shape.

6. The herein described process of producing seamless tubing from sheet metal 55 which consists in forming a strip of sheet metal of suitable width into a tube of non-circular cross section, propelling the tube longitudinally forward at constant speed, forcibly rotating the tube in its non-circular condition to present its seam in a straight line, welding the seam as fast as the tube travels, and, after the seam is welded, compressing the tube to give it a different cross sectional form.

65 7. The herein described process of pro-

ducing seamless tubing from sheet metal which consists in forming a strip of sheet metal of suitable width into a tube of non-circular cross section, propelling the tube longitudinally forward at constant speed, 70 and simultaneously acting torsionally upon the non-circular tube to forcibly twist its seam into a predetermined position and progressively welding the positioned seam.

8. The herein described process of producing seamless tubing from sheet metal which consists in forming a strip of sheet metal of suitable width into a tube of non-circular cross section, propelling the tube longitudinally forward at constant speed 80 and simultaneously exerting rotative pressure upon the non-circular tube to position its seam in a straight line, heating the positioned seam as the tube travels to form a continuous weld, and finally compressing 85 the welded tube to change its cross sectional form.

9. The herein described process of manufacturing metallic tubes from sheet metal which consists in propelling a strip of sheet 90 metal of suitable width longitudinally forward and forming it into a tube of non-circular cross section with its seam in butt relation, rotating the non-circular tube to guide the seam in a straight line, playing 95 a welding flame upon and simultaneously exerting pressure at the straightened seam of the tube to continuously weld the seam as fast as the tube travels.

10. The herein described process which 100 consists in propelling a strip of sheet metal of suitable width longitudinally forward and forming it into a tube of non-circular cross section with its seam in butt relation, exerting a rotative effort upon the tube to 105 cause the seam thereof to assume a predetermined position, playing a welding flame upon the positioned seam and simultaneously pressing the edges to progressively weld the seam as fast as the tube travels, 110 and finally compressing the welded tube to perfect its cross section.

11. The process of manufacturing circular tubing from sheet metal which consists in forming the flat, raw material into a tube of oval cross section, propelling said tube forwardly at constant speed, impinging a welding flame upon the seam thereof as the tube travels, compressing and simultaneously rotating the tube to forcibly twist its seam 120 into proper alinement with the flame, and, after being welded, subjecting the oval tube to an additional forming operation to give it a circular cross section.

12. The herein described process of making seamless circular tubing which consists in preliminarily forming strip metal into an oval tube with its edges in butt relation, moving said tube forward at constant speed, rotatively clamping the tube to forcibly 125 130

aline its seam and maintain its edges in said relation, impinging a welding flame upon the alined seam of the tube, and compressing the welded tube to change it from oval 5 to circular cross section.

13. The herein described process of manufacturing metallic tubing which consists in forming the raw stock into a non-circular tube, moving the tube forward and utilizing 10 the non-circularity of the tube for presenting its seam in a straight line, and exposing the seam to the action of a welding flame as the tube travels.

14. The herein described process of making seamless tubing which consists in initially forming a metal strip of suitable width into a non-circular tube, moving said tube longitudinally forward and utilizing the 15 non-circularity of the tube for straightening it and presenting its seam in a predetermined position, subjecting the seam to the action of a stationary welding flame while the tube is in movement, and simultaneously exerting a welding pressure at the 20 seam of the tube.

15. The herein described process of making metallic tubing which consists in longitudinally rolling a strip of flat metal of suitable width into a non-circular tube with 25 the edges of the strip in substantial abutment, moving said tube longitudinally forward at a constant speed past a welding burner with the seam exposed to the action of said burner flame to join said edges, and 30 then forming said tube to final desired shape.

16. The process of making tubing which consists in longitudinally rolling a strip of metal into a tube of non-circular section having 35 a longitudinal seam formed by the abutting edges of the strip, applying lateral pressure upon the tube and thereby causing it to rotate and position its seam in a predetermined straight line, moving said tube 40 forward and exposing successive portions of the seam to the action of a welding flame.

17. The process of making tubing which consists in rolling up a strip of metal into a tube of non-circular section having a longitudinal seam formed by the abutting edges 45 of the strip, moving said tube forward under lateral compression to forcibly cause the

rotation of the tube and the positioning of its seam, progressively exposing the positioned seam to the welding action of a fine, 55 narrow flame and, after the seam is welded, compressing said tube into circular form.

18. The herein described process of manufacturing metallic tubes that consists in forming a tube of non-circular cross section 60 from strip metal, subjecting it to the action of a drawing device serving to carry it past a heating device and simultaneously adjusting the tube with the seam thereof in proper position with respect to the heating device, 65 said adjustment of the tube following by virtue of the non-circular shape of the tube and the complementary curved portions of the drawing device and, after the tube is welded, subjecting it to a further forming 70 operation to give it a final perfect cross sectional shape.

19. The herein described process of manufacturing tubing which consists in forming the raw stock into a non-circular tube subjecting the tube to the action of a drawing device which acts to grip the tube and because of the non-circularity of the tube automatically twists or torsionally acts upon the tube in manner to aline the tube in a 75 straight line and exposing the tube with the alined seam to a welding flame as the tube travels.

20. The herein described process of making seamless circular tubing which consists in initially forming strip metal into an oval tube with its edges in butt relation, subjecting the tube to the action of a drawing device shaped in such manner that the clamping of the drawing device upon the non-circular tube acting, if the tube is presented out of proper alinement to rotate the tube until it assumes the proper position, impinging a welding flame upon the alined seam of the tube, and compressing the welded tube to 80 change it from oval to other desired cross sectional shape.

In testimony whereof, I have hereunto set my hand this 11th day of March, 1912, in the presence of two subscribing witnesses.

MARSHALL BURNS LLOYD.
